UNITED STATES PATENT OFFICE

STEPHEN D. BAKER, OF NEW YORK, N. Y.

DESIGN FOR AN ASH RECEIVER, OR ARTICLE OF SIMILAR NATURE

Application filed August 5, 1931. Serial No. 40,791. Term of patent 3½ years.

To all whom it may concern:

Be it known that I, STEPHEN D. BAKER, a citizen of the United States, and a resident of New York, in the county of New York and State of New York, have invented a new, original, and ornamental Design for an Ash Receiver or Article of Similar Nature, of which the following is a specification, reference being had to the accompanying drawing, forming part thereof.

The drawing is a perspective view of an ash receiver embodying my new design.

I claim:

The ornamental design for an ash receiver, or article of similar nature, as shown.

STEPHEN D. BAKER.
